DEVICE FOR BUILDING UP ILLUSTRATIONS

Erwin Herz, New York, N. Y.

Application May 27, 1944, Serial No. 537,692

1 Claim. (Cl. 46—21)

This invention relates to a device for building up illustrations of historical and religious events, of stories and particularly religious stories, of fairy tales and the like.

Devices of a similar type consist of individual sheets of cardboard or other suitable materials. These sheets are painted in conformity with the particular subject to be presented. The sheets are so constructed as to be converted by pre-arranged incisions, cutouts, creases and folds into a scenic three-dimensional structure and to be reconverted into the flat condition when not used for the scenic presentation.

Tongues and slots are customarily provided in the sheet to secure the scenic structure in its three-dimensional form.

The novelty and the progress of the invention resides therein that the sheets to be converted into the illustration of stories, fairy tales and the like consist of the pages of the book.

The book pages contain a pictorial portion adapted to be separated therefrom along its outline. The separated portion is provided with suitable means to be converted into a three-dimensional scenic or architectural structure forming the illustration of the historic events, of stories, fairy tales and the like, and after being refattened to be reinserted into the book.

The range of applying the invention is large. The book may consist of pages, each of which may be converted into a scenic and plastic representation of characteristic parts of historical events, of stories and particularly religious stories, of fairy tales and the like narrative matter; a description of the presented scene may be applied to the separable portion of the page.

The invention is described in the following by way of example, reference being made to the accompanying drawings, of which

Fig. 1 shows a front elevation of one page inserted in the book constructed in conformity with my invention.

Fig. 2 shows a front elevation of the separable portion of the page to be converted into a scenic structure and adapted to be easily removed from the page, and

Fig. 3 shows a perspective view of the assembled scenic structure.

The book shown in the drawings consists of a cover 1 and a plurality of pages 2; the front part of the cover may be provided with a suitable title and pictorial illustrations relating to the descriptive matter which is to be presented by the book pages.

One of the pages to be inserted in the book

5 cover is illustrated in the drawings; it consists of a border portion 3 to be retained in the book cover and a center portion 4; border portion 3 also may consist of a single strip to hold the separable portion 4 instead of a frame-like body, as shown; portion 4 is adapted to be separated from the book page along its severed or otherwise separable outlines 23.

10 This separable portion is convertible into a three-dimensional scenic structure and may be refattened for reinsertion into the book page.

15 For its conversion into the self-supporting structure shown in Fig. 3 separable page portion 4 shown in Fig. 1 and Fig. 2 is provided with 20 suitably arranged incisions 8, 21 shown in full lines, creases 9, 14, 15, 20, 22, shown in dotted lines, tongues 10, 16 and slits 11, 17.

25 This separable page portion comprises a base 5, a background 6, two side panels or wings 7 and a front strip 18 connecting the two side wings.

Incisions 8 and creases 9 are provided along the meeting edge of base 5 and side panels 7.

30 Tongues 10 and slits 11 form the connection of these two portions in the upright self-supporting 25 position shown in Fig. 3.

In this position the structure rests on border portions 13 and on parts 12 which serve as a support.

35 Crease 15 is provided to bend the border portion 13 into a supporting flap extending vertically in the position shown in Fig. 3.

Creases 14 are provided at the meeting lines of the side wings 7 and background 6 which render it possible to advance the side wings and to connect the same with the base by tongues 10 and slits 11 in the self-supporting position.

The structure is stiffened by front strip 18 connecting the side wings and provided with tongue 16 to be entered into slit 17.

40 Creases 20 cooperating with incisions 8 render the bending of table 23 in the three dimensional position possible.

45 Various changes and modifications may be made to the details of the invention without departing from the broader spirit and scope thereof, as set forth in the following claim.

I claim:

A device for building up illustrations of historic and religious events, of stories and the like, comprising a book, single pages in the said book, the single book page containing a pictorial portion adapted to be separated from the book page along its outline, the said separable portion being adapted to be converted into a three-dimensional scenic structure and to be reinserted into the

book page, said separable portion being composed of a base, a background, a plurality of side wings and an upper front strip, creases along the meeting lines of the base, the side wings and the background, incisions along the meeting lines of the base and the side wings, tongues and slots in the border portions of the base and the side wings adjacent to the said incisions, a crease and an incision extending along the meeting line of

the said upper front strip, the background and the side wings, a tongue and a slit in the border portions of the said upper strip, and of the one side wing adjacent to the said strip, being thereby adapted to be converted upon removal from the book into an upright self-supporting scenic structure and to be reflatened into its original state for reinsertion into the book.

ERWIN HERZ.
